SIGN

Ross A. Noble, Detroit, Mich.

Application April 9, 1948, Serial No. 145,622

Term of patent 14 years

(Cl. D1—12)

To all whom it may concern:

Be it known that I, Ross A. Noble, a citizen of the United States, residing at Detroit, county of Wayne, State of Michigan, have invented a new, original, and ornamental Design for a Sign, of which the following is a specification, reference being had to the accompanying drawing, forming part thereof.

Fig. 1 is a front elevational view of a sign showing my new design.

Fig. 2 is a rear elevational view of the sign.

Fig. 3 is a side elevational view showing the normal position of the sign as it rests upon a surface.

Fig. 4 is a cross sectional view taken on line 4—4 of Fig. 1.

I claim:

The ornamental design for a sign, substantially as shown.

ROSS A. NOBLE.
